UNITED STATES PATENT OFFICE

WILLIAM H. HOODLESS, OF PHILADELPHIA, PENNSYLVANIA

PUMP

Application filed February 26, 1927. Serial No. 171,344.

The device belongs to the class of portable drainage pumps that are taken from one locality to another for temporary use. Such pumps are placed without being bolted or otherwise secured thereto on improvised rests or supports, which usually extend outward over water or mud. The driving mechanism must usually be placed at quite a distance to secure a sufficiently firm support. The present device, in accordance with the accepted practice, is of the screw lift type, and consequently the rotating pump shaft must be driven very rapidly. The pump must often be transported to localities where no electric power is available, hence a belt and pulley drive is the only means of driving it and the pull of the long belt often required brings a heavy overturning pull on the pump pulley tending to overturn the pump. This device is intended to meet these conditions by using a structure in which the pump pulley is placed very nearly on a level with the pump rests that carry the pump and would form, if the pump were overturned, the fulcrum about which it would turn. The pump discharge is located well below these pump rests, and the barrel of the pump is rigidly and strongly secured to these upper parts. The lower part only of the pump barrel (the part below the discharge) is normally filled with water, and the weight of this water combined with the leverage arising from its position, will insure a steady position to the pump structure. My pump structure accomplishes these purposes. It has an upper portion, which is a housing containing the driving gear placed at a level very little above pump rests that extend broadly, on either side of it, and a barrel with its discharge outlet well below the pump rests and these parts being rigidly secured together. This structure is hereinafter described and claimed.

Fig. 1 is a side elevation of the pump. Fig. 2 is a section on line 2—2 of Fig. 1. Fig. 3 shows a plate before being curved and flanged that forms part of the discharge. Fig. 4 is a section on line 4—4 of Fig. 1. Fig. 5 is a vertical section on an

enlarged scale of the pump rest structure, the driven gears and their housings, the connecting parts between the pump rest and the gear housings and the extreme upper end of the body; the pulley and pulley shaft housing being shown as in elevation. Fig. 6 is a plan view of the pump rest structure and the parts adapted to secure it to the gear housing. Fig. 7 is a vertical section of the body plate of the intake of which Fig. 8 is a plan view. Fig. 9 is a section of the foot bearing for the screw shaft. Fig. 10 an elevation of the lifting screw, and Fig. 11 a vertical section of the discharge.

The driven gears are bevel gears 62 and 66. The spindle of the gear 66, and of the driving pulley 30, is the shaft 15, which has bearings in the housing formed of the parts 31, 47, 67, and 68. This housing is firmly secured to the collar 48, of the part 32, of the larger part of the housing 34 of the gearing. The shaft 15, and its housing and the bevel gears 62 and 66, are all stock articles and purchasable in the form used in the pump. The main part of the gear housing is formed of the part 34, to which is secured the top plate 33, and the bottom plate 35, which have the annular and inwardly projecting walls 69 and 63 to contain roller bearings 64, 70, and 71.

The housings formed of the above named parts is firmly secured above and adjacent to the pump rest, by mounting it upon and securing it firmly to the bearing 72, which is preferably in the form of a ring fitting snugly around a top plate 28 of a gland attached to the bottom plate 35 of the gear housing. The bearing 72 is carried by inwardly sloping struts 29 which are secured at their feet 77 to the bearing plate 41 of the pump rest, and at their heads 74 to the bearing 72. The bearing plate 41 is preferably flanged to give it rigidity without too much weight and is provided with the bearing lip 14, below the flange 13, extending preferably the whole length of the plate 41, which rests on the supports 43, 43, which can be anything strong enough to carry the pump's weight, and to which ordinarily the pump need not be fastened in any way.

The bearing plate 41 extends very broadly, and well beyond the sides of the gear housings and this and the arrangement of the supporting elements by which the gear housing is carried tend to keep the pump from being tilted by the belt pull on the pulley 30. The bearing plate 41, in practice, is strengthened by the cover plate 175, which has the flanges 176 covering the edges of the plate 41.

Seats for the roller bearings in which the shaft 45 rotates, are provided at the upper and lower parts of the gear housing in the cups formed by the walls 63 and 69. As these bearings are positioned at some distance from each other the axis of the shaft is fixed by them. Bearings at both of these cups or at one of them also carry the weight of the shaft 45, the gear 62, and the screw 54, and of the water lifted by it. In the construction shown the roller bearing 64, at the top of the gear used to align the shaft only as is also the roller bearing 70 at the bottom of the housing, but the roller bearing 71 at the bottom of the housing is a carrying bearing supporting the shaft 45 and its attached elements. This insures its very free rotation even when weighted down by the water the screw is lifting. The gear housing preferably should contain a quantity of oil or grease sufficient to cover the gear 62, and the roller bearing supporting the shaft 45 will run submerged. A gland is located at the lower side of the gear housing and consisting in practice of the packing container 73, the nut 76, and the compression element 75. The upper part of the packing container 73 may form a plate 28 that can be secured to the bottom of the gear housing and can be shaped to fit inside the bearing 72.

The pump body 44, the breadth of which exceeds considerably the width of the gear housing, is hung directly from the pump rest. In practice, it is secured to the bearing plate 41 by a hanger 42, and in practice both hanger and pump body are circular. It can be made of quite thin sheet metal; for there can be no twisting or bending strain of any great amount on it, thus adding to the portability of the pump. The discharge can be made very conveniently by shaping the ends of the plate 16 so that they will fit into the discharge mouth piece 58 and its middle portion form part of the pump body and the portions between the middle portion and the ends, form the sides of the discharge. The plates 49 form the upper and lower portions of the discharge mouth the form of which the plates before the flanges 59 are bent up as illustrated in Fig. 3. This construction gives the outlet port at the pump body walls a width substantially equal to the width of the pump body and with a nearly level bottom, and is simple and cheap, and

insures the complete discharge of the water before it rises much above the bottom. It will be seen that by this construction a comparatively small volume of water concentrated at the lower end of the pump body which, as before stated, is of large diameter, has a moment that prevents the rocking of the pump rests on the supports without putting too great a weight on the supports, which are almost of necessity light and insecurely anchored.

The intake is illustrated in Figs. 1 and 4 as a built up structure and in Figs. 7 and 8 as partly formed by a casting, which I regard as preferable though the two constructions are essentially alike. The louvers 52 can be used to prevent the swirling of the water below the lifting screw. The hangers 50 may be bolted on, as shown in Figs. 1 and 4, or form part of a casting as shown in Figs. 7 and 8. A combined reinforcement and union 98 can be secured to the bottom of the pump body, as shown in Fig. 1, to which the hanger carrier 57 can be attached or a somewhat differently shaped reinforcement and union 99, as indicated in Figs. 7 and 8, used.

The lower bearing for the shaft 45 is carried from a standard 53, preferably peak-shaped and upwardly projecting centrally from the bottom of the intake, thus assisting in directing the inflow of the water to the lifting screw. This standard has a pocket that in the form of intake shown in Figs. 1 and 4, has a lining 51 of bearing metal. In the form shown in Figs. 7 and 8 the standard is an integral portion 89 of a casting with the hangers 50 and has a pocket preferably with a lining 90, which is cupped out spherically at its upper portion 97, and contains an adjustable journal box 95, with a lining of bearing metal, 94 forming the bearing for the shaft 45. The upper portion of the journal box fits the portion 97. Below the spherically cupped out portion the pocket is extended to give play for the adjustment of the journal box. The adjustment is made permanent by the set screws 91, 91.

The water lifting screw in practice consists of the hub 88 to which are bolted the blades 54, 54. The hub is suitably secured to the shaft 45. The shaft 45 has the union consisting of the plates 38 and 39 on the hubs 40 and 37; so that, when additional sections are added to the pump body, the shaft 45 also can be lengthened. The additional sections can be added to the pump body either below or above the discharge.

I claim

1. A portable drainage pump intended to be carried from light supports and provided with pump rests that are widely extended and are carried unconnectedly by said supports, comprising in combination a

pump barrel positioned below said rests and carried rigidly therefrom and having an intake and discharge mouth below the same, a water lifting screw in said barrel, gearing positioned above said pump rests, supports for said gearing extending from said rests to said gearing, a vertical shaft extending from said gearing to said water lifting screw, and a pulley connected to said gearing; the discharge mouth of said barrel being positioned at such a substantial distance below the pump rests that the moment of the water in the barrel will exceed the moment caused by the operation of the driving of said pulley.

2. The device as defined in claim 1 in combination with a horizontal plate carried by said pump rests, and connections between said plate and said rests and between said 20 plate and said pump barrel.

3. In a portable drainage pump of the type intended to be carried from light supports, and having a pump barrel carried below the level of the pump rests, which 25 rests are widely extended and depend for support upon said light supports, said pump having a rotary water lifting screw in said barrel, the combination comprising a driving gear having a driving pulley, said pulley 30 being positioned close to the level of the said rests, a driving shaft connecting said gearing and lifting screw, a horizontal plate secured to and carried by said pump rests, nearly at their level, said pump barrel being hung from said plate and extending 35 downwards and having a discharge mouth below the said plate; the said pulley being positioned at a less distance above said pump rests than the discharge mouth of the pump 40 is positioned below the same.

4. The device as defined in claim 3 in combination with inwardly inclined struts supported at their lower ends from said 45 pump rests by being bolted to said horizontal plate, and being connected to and supporting said gearing.

5. The device as defined in claim 3 wherein the drive pulley is centrally disposed with reference to said pump rests in 50 combination with inwardly inclined struts extending between said pump rests and said gearing and supported at their lower ends by said pump rests.

WILLIAM H. HOODLESS.
